(57) **CLAIM**

The ornamental design for a dust pan attachment, as shown and described.

DESCRIPTION

FIG. 1 is a perspective view of an embodiment of a dust pan attachment showing a new design;

FIG. 2 is a top view of the dust pan attachment illustrated in FIG. 1;

FIG. 3 is a front view of the dust pan attachment illustrated in FIG. 1;

FIG. 4 is a bottom view of the dust pan attachment illustrated in FIG. 1;

FIG. 5 is a rear view of the dust pan attachment illustrated in FIG. 1;

FIG. 6 is a right side view of the dust pan attachment illustrated in FIG. 1; and,

FIG. 7 is a left side view of the dust pan attachment illustrated in FIG. 1.

The broken lines in the drawings illustrate the portions of the dust pan attachment that form no part of the claimed design.
